UNITED STATES PATENT OFFICE.

DAVID M. BOWEN, OF LOS ANGELES, CALIFORNIA.

RADIATOR.

1,311,797.

Specification of Letters Patent. Patented July 29, 1919.

Application filed December 13, 1916. Serial No. 136,799.

To all whom it may concern:

Be it known that I, DAVID M. BOWEN, a citizen of the United States, residing at Los Angeles, in the county of Los Angeles 5 and State of California, have invented a new and useful Radiator, of which the following is a specification.

My invention relates to the art of heating and ventilating, and the principal object of 0 the invention is to provide a new and useful form of radiator unit for use in that art.

While I have illustrated and described a radiator unit which is made an integral part of a hot air furnace, I do not wish to be 5 understood as limiting myself to this application alone, the term "radiator unit" being used in the specification and the claims to denote a device for transferring the heat of combustion of heated gases passing 0 through the interior of the device to a body of air surrounding it. My radiator unit may be used with or without a jacket, as will be obvious from the following description.

5 In the heating and ventilating art, the cost of construction is by far the greatest factor, and my invention is especially designed to be built up out of sheet iron or steel in an ordinary tin shop without requiring special forms or tools for its production, all of the sheet metal therein being disposed in plane surfaces and all of the angles being plane dihedral ones which are readily formed up by the ordinary sheet 0 metal working tool.

The efficiency of all sorts of heating devices may be measured by the ratio of the average initial temperature of the products of combustion to the average temperature 0 of the flue gases, the lower the temperature of the flue gases, other things being equal, the greater the efficiency of the heat. My invention is especially designed to extract the greater portion of the heat from the 5 products of combustion so that the temperature of the flue gases is very low and the efficiency is very high. Where air is subjected to variations in temperature, and especially where heated air which is loaded 0 with water vapor is cooled, condensation is likely to take place, and it is a further object of my invention to provide means for preventing an accumulation of the water of condensation.

5 Further objects and advantages will be

made evident hereinafter, or will be obvious to one skilled in the heating and ventilating art from a perusal of the annexed specification and drawings.

In these drawings,

Figure 1 is a side view of a hot air furnace equipped with my invention.

Fig. 2 is a section through the outer jacket of the apparatus shown in Fig. 1, the radiator unit being shown in elevation.

Fig. 3 is a section on a plane represented by the line 3—3 of Fig. 1, this plane being viewed in the direction of the arrows.

Fig. 4 is a cross-section on a plane represented by the line 4—4 of Fig. 3.

Fig. 5 is a cross-section on a plane represented by the line 5—5 of Fig. 2.

Fig. 6 is a perspective view of a portion of my heater certain of the parts being broken away to better illustrate the invention.

Fig. 7 is a section on a plane represented by the line 7—7 in Fig. 1.

In the form of my invention illustrated in these drawings, a hot air furnace is shown consisting of an outer jacket 11 which is 80 perforated as shown at 12 near its lower end, so that the lower portion of its interior is in open communication with the outer air. Any desired number of hot air pipes 13 may be connected into the top of the jacket and 85 connected to registers located in the different rooms. Located inside the jacket 11 is a radiator unit 20, this unit consisting of a rectangular box having sides 21 and 22, ends 23, and a top 24. A flue 25 passes through the jacket 11 and communicates with the top of the interior of the radiator unit 20, this flue 25 being connected by suitable piping, not shown, with a chimney which is also 90 not shown. Located in the bottom of the radiator unit 20 is a burner 30 adapted to use gas. As the burner 30 forms no part of the present invention, various other types of gas or oil burner may be substituted therefor, or a grate in which solid fuel may be 95 burned may be substituted without in any way departing from the spirit of my invention, the word burner being used in the specification and the claims to denote all of these obvious mechanical equivalents.

Formed in the ends 23 of the radiator unit 20 are a series of inclined slots 40 and formed in the sides 21 and 22 are a series of horizontal slots 41. The slots 41 extend 100 completely across the sides 21 and 22 join- 110

ing the slots 40 which extend only partly across the ends 23. Set into the slots 40 and 41 are a series of sheet metal inserts 50, these inserts having all of their ends joined 5 to the walls of the radiator unit 20 in a gas tight relationship therewith so that the completed unit will contain the heated gases from the burner 30 without allowing any of these gases to leak into the space between 10 the radiator unit 20 and the interior of the jacket 11. The slots 40 and 41 are so located, and the inner or closed end 51 of each insert is so formed, that a space is left between the end 51 and the nearest wall of the 15 radiator unit 20. The slot 41 is also so inclined that the closed end 51 of the inserts 50 is somewhat lower than the mouth 52 of the insert.

A series of hot air flues 60, which are rectangular boxes of sheet iron, are set into the sides 21 and 22 of the radiator unit 20, connecting the lowest portion of the inserts 50 with the space between the jacket 11 and the radiator unit. The hot air flues 60 are so proportioned that a series of combustion flues 61 are formed, these flues connecting each space within the radiator unit 20 with the next space above. The lower portion of the radiator unit 20 is open to admit air for 25 combustion and for mixing it with the products of combustion to produce a lower temperature thereof.

For the purpose of increasing the efficiency of my heater, I use a series of cold air flues 70, these flues being rectangular in form and slightly smaller than the hot air flues 60, into which their inner ends are inserted. The cold air flues 70 project through the walls of the jacket 11 and serve to supply 30 cold air to the lowest portion of the inserts 50. In practice the cold air flues 70 may be omitted from the two lower inserts 50.

The method of operation of my invention is as follows: The burners 30 being supplied 35 with gas, which is lighted, the products of combustion are somewhat diluted with air, passing upwardly through the interior of the radiator 20 and outwardly through the flue 25. In their passage upwardly they pass 40 around the inserts 50 and through the flues 61. It will be noted that to do this these heated gases must follow a tortuous path 45 impinging on the sheet iron surface forming the walls of the radiator unit 20 and the 50 inserts 50. It will also be noted that each of the inserts 50 forms with the walls of the radiator unit 20 a sort of pocket, the top of which is somewhat higher than the outlet. By making a succession of pockets in this 55 manner it is possible to greatly delay the 60 passage of the hot gases through the unit and thereby extract a large portion of their heat before they are allowed to pass into the flue 25. Part of the air in the space between 65 the jacket 11 and the radiator unit 20

also follows a tortuous path through the interior of the inserts 50 entering these inserts from either end.

The two lower inserts 50 also take air from between the jacket 11 and the radiator unit 20 through the hot air flues 60. The upper inserts 50 are supplied with cold outside air through the cold air flues 70.

No pockets are formed in which the air to be heated can collect, this air passing constantly upward between smooth surfaces during its passage through the heater.

Due to the considerable production of water vapor by the combustion of the gas, there is considerable likelihood of condensation taking place inside the unit 20. The inclination of the inserts 50 being downward, any water condensing thereon drains off, and rapid rusting away of the sheet metal surfaces, due to moisture standing thereon, is prevented.

While I have spoken of my invention as constructed of sheet iron or steel, it is obvious that it could be constructed of other sheet material, or by dividing it into suitable sections it could be cast from iron or other material. All such obvious minor changes form a part of my invention, and I reserve the right to make any such modifications, limiting my invention only by the annexed claims.

I claim:

1. An air heater comprising a rectangular box composed of sheet iron; a burner in the bottom of said box, a flue in the top of said box; a series of inserts set into open slots in said box, said inserts being open at one side and at each end to the space surrounding the box, said inserts making a continuous gas tight joint with the ends and sides of said box; a series of hot air flues, each flue connecting the inner end of one of said inserts with the space on the side of the box opposite the mouth of the insert; a shell having openings formed in the lower end thereof through which cold air is admitted to the heating space between said shell and said rectangular box; means for taking air from said heating space; and a series of cold air flues each extending through an opening in said shell and connecting with the outer end of one of said hot air flues.

2. An air heater comprising a rectangular box composed of sheet iron; a burner in the bottom of said box; a flue in the top of said box; a series of inserts set into open slots formed alternately from either side of said box, said inserts being open at one side and at each end to the space surrounding the box, said inserts making a continuous gas tight joint with the ends and sides of said box; a series of hot air flues, each flue connecting the inner end of one of said inserts with the space on the side of the box opposite the mouth of the insert; a shell inclosing

said radiator unit and having openings formed in the lower end thereof through which cold air is admitted to the heating space between said shell and said rectangular box; means for taking air from said heating space; and a series of cold air flues each extending through an opening in said shell and connecting with the outer end of one of said hot air flues.

10 3. An air heater comprising a rectangular box composed of sheet iron; a burner in the bottom of said box; a flue in the top of said box; a series of inserts set into open slots in said box, said inserts being open at 15 one side and at each end to the space surrounding the box, each insert being so inclined that it is higher at the point where it joins the said box than at any other point, said inserts making a continuous gas tight joint with the ends and sides of said box; a series of 20 hot air flues, each flue connecting the inner end of one of said inserts with the space on the side of the box opposite the mouth of the insert; a shell inclosing said 25 radiator unit and having openings formed in the lower end thereof through which cold air is admitted to the heating space between said shell and said rectangular box; means for taking air from said heating space; and 30 a series of cold air flues each extending through an opening in said shell and con-

nected with the outer end of one of said hot air flues.

4. An air heater comprising a rectangular box composed of sheet iron; a burner in the bottom of said box; a flue in the top of said box; a series of inserts set into open slots formed alternately from either side of said box, said inserts being open at one side and at each end to the space surrounding the 40 box, each insert being so inclined that it is higher at the point where it joins the said box than at any other point, said inserts making a continuous gas tight joint with the ends and sides of said box; a series of 45 hot air flues, each flue connecting the inner end of one of said inserts with the space on the side of the box opposite the mouth of the insert; a shell inclosing said radiator unit and having openings formed in the 50 lower end thereof through which cold air is admitted to the heating space between said shell and said rectangular box; means for taking air from said heating space; and a series of cold air flues each extending 55 through an opening in said shell and connecting with the outer end of one of said hot air flues.

In testimony whereof I have hereunto set my hand at Los Angeles, California, this 60 5th day of December, 1916.

DAVID M. BOWEN.
